UNITED STATES PATENT OFFICE.

NEWTON L. HALL, OF LA SALLE, ILLINOIS.

FASTENER OR CONNECTER FOR CORRUGATED ROOFING OR SIDING SHEETS.

Application filed February 10, 1923. Serial No. 618,302.

To all whom it may concern:

Be it known that I, NEWTON L. HALL, a citizen of the United States, residing at La Salle, in the county of La Salle and State 5 of Illinois, have invented certain new and useful Improvements in Fasteners or Connectors for Corrugated Roofing or Siding Sheets, of which the following is a specification.

10 This invention relates to means for fastening or connecting corrugated or flat roofing sheets or siding sheets to beams, purlins, girts or other structural elements.

At the present time sheet metal roofing and siding sheets, either plain or corrugated, are connected or attached to the purlins, rafters, beams or girts or roofs or other structures either by driving a nail through the corrugated sheet or other sheet into the 15 wood rafter, beam or nailing strip, by holding the corrugated or other sheet to the structural elements by means of a stove bolt, by attaching to the under face of the sheet by means of a bolt a metallic clip which engages beneath the flange of an angle iron or purlin, by the use of straps which pass beneath the purlin or other element and which are angularly bent at their outer ends and bolted to the sheet, or by the use of tie wires 20 headed at one end which are forced through the sheet metal and extend along the outer face of the purlin, then beneath the base flange thereof, and then are bent or clinched upward around the lower flange of the purlin. 25

Each of these methods of connecting sheet metal, and particularly corrugated metal, to the rafters, purlins or other structural elements is objectionable. The wood nailing strip construction is not fireproof and is, therefore, not used to any extent except in the cheapest construction. The bolted or soldered clip engaging the purlin is not a positive connection and allows the roofing 40 sheet or siding sheet to rattle. The stove bolt connection is never sufficiently tight and is always subject to rapid corrosion and is inconvenient to apply. The strap connection requires that the strap shall be previously formed, is expensive, clumsy of application, and the bolts develop their strap strain around the bend of the strap. The strap method of holding corrugated sheets or plain sheets to the purlin is the most 45 proved fastener used today, but it is not perfect. The fastening device cannot be

tightened up to a degree which will cause the sheet to cling to the structure and, therefore, the roofing sheets are liable to rattle in the wind. Furthermore, all dimensions 60 have to be perfect to make a correct fastener. The same is true of the clinch nail or tie wire method. This in turn is never absolutely tight. Once loose it remains loose. The bend in the tie wire can never be made 65 around the purlin so as to secure a proper strain upon the tie wire or clinch nail which will hold the sheet firmly and securely to the purlin, whether the same is of angle iron or channel iron. 70

The general object of my invention is to provide means for connecting roofing or siding sheets to purlins or equivalent structural elements, which connecting means is so formed that strain is applied to draw 75 the sheet against the purlin at the side of the purlin and not below the purlin.

A further object is to provide a connecting device of this character which includes a stirrup, as it may be called, which is disposed below the lower flange of the purlin or against the edge of the outwardly projecting flange or girt, this stirrup being pre-formed to fit the flange over the purlin or the girt and which also includes two headers, as they may be termed, or headed wires adapted to be disposed through the sheet and on each side of the purlin or above and below the girt which are engageable by twisting with the ends of the yoke or stirrup, 80 85 this twisting process acting to tighten up on the stirrup and headers and draw the roofing sheet firmly into contact with the purlin, this twisting occurring at the sides of the purlin and not below the inner flange thereof so 90 that the strain created by this twisting operation will act directly on the sheet and this twisting will cause the two ends of the stirrup and the two headers to be tightened up on a straight line between the purlin or 95 girt and the sheet so that the parts will fit closely to the purlin or girt.

A still further object is to provide a device of this kind which is very simple, which may be cheaply made in large quantities, and 100 which is particularly easy to apply.

Other objects will appear in the course of the following description.

My invention is illustrated in the accompanying drawings, wherein:— 110

Figure 1 is a sectional view through a purlin and a corrugated roof applied there-

to and showing my improved connector applied;

Figure 2 is a side elevation of the purlin and a sectional view of the roof, showing my 5 connectors;

Figure 3 is a like view to Figure 1, but showing the connector partially applied and before a full twist has been made;

Figure 4 is an elevation of the stirrup 10 which forms part of the connector;

Figure 5 is a sectional view through a girt and siding showing an adaptation of my improved connector to such a structure;

Figure 6 is a sectional view on the line 15 6—6 of Figure 7, showing a modification in the form of stirrup and the manner in which the headers are engaged therewith;

Figure 7 shows a side elevation of a purlin, showing a modified form of connector 20 fully twisted, and at the right a modified form of the connector partly twisted;

Figure 8 is a perspective view of the stirrup shown in Figures 6 and 7 before it is twisted;

Figure 9 is a like view to Figure 1, but showing a modified form of connector before the connector is engaged with the purlin;

Figure 10 is a like view to Figure 9, but showing the headers engaged with each other 30 and ready to be twisted;

Figure 11 is an elevation of one of the headers shown in Figures 9 and 10 before it is inserted through the sheet metal;

Figure 12 is a like view to Figure 10, but 35 showing the headers completely twisted.

Referring particularly to Figures 3 and 4, it is to be noted that my connector comprises two headers or wires 10 having heads 11 at their upper ends and a stirrup 12.

40 The stirrup 12, as illustrated in Figure 4, is U-shaped so as to provide arms 13 which are at right angles to the lower portion of the stirrup and at their upper ends these arms are initially outwardly and downwardly extended at 14.

45 In Figures 1, 2 and 3, I illustrate how this connector is applied to hold a corrugated sheet metal roofing B to a purlin A. The headers are passed through perforations in the roofing, preferably through the crests of the corrugations, on each side of the purlin A. These headers are initially straight and are made of wire of sufficient flexibility so that the ends of the headers may be twisted. The stirrup 12 is then applied beneath the purlin, as illustrated in Figure 3, and then the lower ends of the headers are bent upward so as to form hooks, as illustrated on the left hand side of Figure 5. The lower ends of both headers are bent upward and then these hooks so formed are intertwined, as shown at 15 in Figure 1. The intertwisting of the wires forming the headers 10 with the upper ends of the arms 13 draws the stirrup upward against the

lower flange of the purlin and draws the sheet B against the upper face of the purlin. By twisting the interengaging ends of the stirrup and headers at the sides of the purlin a strain may be placed upon the headers and 70 stirrup greatly in excess of all requirements and this strain is so great that it is easily possible to continue the twisting and draw the corrugation out of the sheet at the header. If the stirrup 13 were left off and 75 the header wires 10 were simply brought down beneath the purlin and twisted, a strain would be developed, it is true, but this strain would be across the lower flange of the purlin and not between the lower 80 flange and the corrugated sheet and this strain would create only an indirect influence on the sheet.

85 My preferable construction is illustrated in Figure 1 and develops the strain where it is required, that is between the base of the purlin and the sheet and this is done in a straight line, that is twisting the header wires 10 and the stirrup 13 at the point 15 causes the shanks of the headers and the arms 13 to be drawn into a straight line and tightened until the sheet B is drawn firmly against the purlin, as illustrated in Figures 1 and 2, there being no slack which will permit any movement of the sheet metal in any 90 way, the construction, however, permitting the expansion and contraction of the sheet metal. In other words, this connector may be tightened up to any degree desired and, as before remarked, it may be tightened to 95 such a degree that the corrugations will be flattened if desired.

100 In Figure 5 I show a form of my invention which is adapted for the purpose of holding a sheet metal siding B' to an angle iron girt A'. In this case the headers 10^a are of practically the same construction as the headers 10, but one of these headers is angularly bent so as to extend upward and outward toward the outer margin of the upper flange of the angle iron A'. I have shown washers 16 of lead or like soft metal disposed between the heads 11 of the headers and the sheet metal. The stirrup 12^a is in principle exactly the same as the stirrup 12 except that instead of being approximately 110 U-shaped it is approximately V-shaped so as to provide arms 13^a at a relatively acute angle to each other. These arms 13^a are adapted to be engaged and intertwined with the ends of the headers 10^a in the manner heretofore described. It will be seen in this 115 form of the invention that the strain applied by twisting is in direct line between the extremity of the girt A' and the sheet metal so that a maximum stress may be applied to the headers to hold the sheet metal in place.

120 In Figures 6, 7 and 8, I have shown a slightly modified embodiment of the invention 125

tion applied for the purpose of holding the sheet B to the purlin A. In this case the stirrup 12^b is made of a double strand of wire so as to form a double loop but having 5 the upwardly extending arms 13^b as previously described, with which loops the extremities of the headers 10^b are engaged. The extremities of the headers 10^b are passed through the loops and then twisted upon the 10 shanks of the headers, as illustrated in Figures 6 and 7, and then the loop or stirrup is itself twisted at 15^b so as to place a strain upon the headers and draw the sheet B into close contact with and attach it securely to 15 the purlin. While the form of the invention shown in Figures 6 and 7 will give good results, the preferable form is that shown in Figures 1 to 5, that is where the stirrup is formed of a single wire, as this is simpler, 20 cheaper and yet thoroughly effective.

The stirrups and the headers will be made of suitably sized iron wire properly galvanized or tinned, or these wires may be made of some rust-resisting metal such as aluminum or Monel metal. The stirrups will be made to fit different sized purlins, that is the base dimension of the cross bar of the U-shaped stirrup will be formed to fit different sized purlins. Obviously, of course, the 25 headers may also be changed in length to suit purlins having different depths. The lower corners of the stirrup are bent sharply so as to fit neatly over the purlin. These stirrups are initially bent for the reason that bending the wire over a purlin when the sheet is in position does not develop a sharp bend and it is very difficult by twisting the wire or by any other means to secure a good sharp bend. Obviously pre-bending these 30 stirrups and making the stirrups to fit different sized standard purlins makes the device much easier of application and permits the connectors to be applied more readily and quickly to the structure than if each 35 stirrup has to be separately bent.

I am aware of the fact that it has been proposed to hold a sheet metal covering to a purlin by means of two headed shanks extending through the sheet metal, these 40 shanks being of flexible material and the shanks embracing the purlin or other structural element and being twisted together at a point remote from the sheet metal or the heads of the shanks. Such a connector, 45 however, as this is open to objections, in that it is impossible to secure a thoroughly tight and close connection between the sheet metal and the purlin or other element. If such a means of attachment is applied to a channel iron structural element such as shown in Figure 1, the intertwist of the two shanks will come immediately beneath the lower flange of the structural element and the wire from which the shanks are made will be 50 sharply bent at the corners of the structural

element, which will prevent the twist from taking up slack in those portions of the shank which extend on each side of the structural element. The same objection would apply were the shanks intertwined 55 with each other on the side of the structural element because one of these shanks would have to be sharply bent around the corner of the purlin. It is necessary that both shanks shall remain straight except for the 60 twist at the extremities of the shank and that there shall be no pull over or across a corner of the structural element.

In Figure 9, I show another form of the invention which embodies the principle 65 thereof, though it only consists of two members. In this figure, A, as before, indicates the purlin and B the corrugated sheet. The headed member 10^c is formed, as illustrated in Figure 11, with a bight 17 at its middle 70 and the extremity of this member is bent into a hook at 14^c. Associated with the header 10^c is a second header 10^d of relatively short wire having its lower extremity bent into a hook to engage with the hook 75 14^c. The lower portion of the header 10^c below the bight 17 may be pre-formed to constitute a stirrup, though not necessarily so, and when the end 14^c is engaged with the hooked end of the header wire 10^d, then 80 the bight 17 may be twisted and the hooks 14^c twisted, as shown in Figure 12, so as to draw the headed ends of the headers 10^c and 10^d toward the lower portion of the connector and draw the sheet metal B against 85 the purlin A. Here again the strain is applied equally on both sides of the purlin and in effect there is a stirrup but this stirrup is made integral with one of the headers 10^c.

It will be noted that the header 10^c has 90 initially the form shown in Figure 11, the bight 17 having more or less divergent end portions so that the header can be inserted through the hole in the sheet, after which the loop is closed or drawn together, as 95 shown in Figure 10. This drawing together of this bight or loop 17 is done before the wire is bent around the purlin, the free end of the header 10^c is bent to form the stirrup portion, and the hooked end 14^c engaged 100 with the hooked end of the header 10^d. The bight or loop 17 is then twisted, as are the hooked ends 14^c.

One advantage of this device over that 105 illustrated in Figures 1 to 4 is that the stirrup requires both hands while placing, while the header shown in Figure 11 gives 110 a much greater freedom of operation. This header 10^c must be formed sufficiently to be inserted through the hole in the sheet metal 115 and manipulated into position, after which the semi-circular bend is pinched together, as shown in Figure 10. It will be seen that 120 in this construction there is a twist or take-up on each side of the purlin so that the 125 130

strain is even on both headers and there is no danger of pulling the stirrup portion around the corner of the purlin. It will be seen that in the one type of fastener the twist 5 is transverse to the strain and in the other type of fastener it is longitudinal to the strain.

It will be seen that with this construction any slack that may develop can be easily 10 taken up at any time, and it will be seen that any side twist removes the slack in direct line between the corner of the purlin and the edge and acts equally on both sides of the purlin. Of course, it will be understood 15 that after the twist is formed, as at 15, the free ends of the wires which may project out are to be cut off so as to give a neat appearance.

Attention is directed to the fact that the 20 twists employed in this connector are arranged at the sides of the purlin and accordingly will not obstruct or interfere with any structure below the purlin.

I claim:—

25 1. A connector of the character described comprising a pair of headed shanks of pliable material, and a stirrup bent upon itself to provide two arms of pliable material and adapted to be engaged with said shanks and twisted to reduce the distance between said member and the heads of the shanks.

30 2. A connector comprising a pair of headed shanks, the shanks being of pliable material, and a stirrup having two arms extending in approximate line with the shanks formed of pliable material and adapted to be intertwined with the shanks.

35 3. A connector of the character described comprising a pair of shanks having heads, the shanks being of pliable material, and an approximately U-shaped stirrup having arms of pliable material initially formed with hooks around which the ends of the shanks may be bent the bent ends of the shanks thus forming hooks, the hooks so formed on the ends of the shanks and the hooks on the stirrup being adapted to be intertwined to draw the stirrup toward the 40 heads of the shanks.

45 4. The combination with a sheet of metal and a structural element upon which the metal is applied, of means for holding the sheet to the structural element comprising a pair of headed shanks inserted through the sheet and having their heads operatively bearing thereagainst, the shanks being of pliable material and a stirrup angular in 50 form engaging around the structural member remote from the sheet and having its ends of pliable material intertwined with the ends of the shanks.

55 5. The combination with a sheet and a structural element to which the sheet is applied, of means for holding the sheet to

the structural element comprising a pair of headed shanks disposed through the sheet on each side of the structural element, the shanks being formed of pliable material, and a stirrup engaging over that portion of the structural element remote from the sheet and having arms extending on each side of the structural element, said arms being of pliable material and intertwined with the ends of the shanks. 70 75

6. The combination with a structural supporting element and a sheet applied thereto, of means for holding the sheet against the structural element comprising a pair of headed shanks disposed on each side of the structural element, and a stirrup engaged over that portion of the structural element remote from the sheet, the stirrup being engaged with the ends of the shanks, the stirrup and shanks being of pliable material whereby they may be twisted to draw the stirrup toward the heads of the shanks and draw the sheet against the structural element. 80 85

7. Means for holding a sheet of material to a structural element comprising a pair of headed shanks less in length than the depth of the structural element with which they are to be used, and a stirrup adapted to extend over that portion of the structural element remote from the sheet and having two arms extending approximately parallel to the shanks and engaged therewith, the stirrup and shanks being of pliable material whereby they may be 90 95 twisted to thereby draw the stirrup toward the heads of the shanks and the sheet against the structural element. 100

8. As an article of manufacture, a connector for connecting sheets of material, of a structural supporting element comprising a pair of pliable shanks having heads, and a stirrup initially approximately U-shaped in form to provide two arms of pliable material, the arms at their extremities being formed with returned bends, the extremities of the shanks and said returned bends being adapted to be intertwined to draw the stirrup toward the headed ends of the shanks. 105 110 115

9. The combination with a structural element and a sheet metal covering supported thereby, of means for holding the sheet metal covering to the structural element comprising members passing through the sheet metal and extending on each side of the structural element and over that portion of the structural element remote from the sheet metal, said members being so formed that strain may be applied to reduce the length 120 125 of said members at the side of the structural element.

10. A connector of the character described formed of pliable wire and formed to provide a stirrup portion adapted to engage 130

over and partially embrace a structural element, and two shanks having heads adapted to engage upon the outside of a sheet of metal to be held to the element, one of the 5 shanks being so formed at a point spaced from the point of engagement between the stirrup and structural element that a twisting strain may be applied thereto to thereby reduce the total length of the connector and 10 draw the sheet metal toward the structural element.

11. A connector of the character described formed of pliable wire and formed to provide a stirrup portion adapted to engage 15 over a structural element, and two shanks having heads adapted to engage upon the outside of a sheet of metal to be held to the element, both of the shanks being formed so that a twisting strain may be applied there- 20 to thereby reduce the total length of the connector and draw the sheet metal toward the structural element.

12. A connector of the character described formed of pliable wire and formed to pro- 25 vide a stirrup portion adapted to engage

around and partially embrace the lower edge of a structural element, and a shank having a head adapted to engage upon the outside of a sheet of metal to be held to the element, the shank and stirrup portion having their 30 adjacent ends adapted to be twisted together at the side of the structural element and intermediate the adjacent corner of the element and the sheet to thereby reduce the 35 total length of the connector and draw the sheet metal toward the structural element.

13. The combination with a structural element and a sheet metal covering supported thereby, of means for holding the sheet metal covering to the structural element 40 comprising a stirrup portion adapted to engage around and partially embrace the free edge of the structural element, and a shank having a head adapted to engage upon the outside of the sheet of metal, said shank and the stirrup having intertwined portions disposed between the free edge of the structural element and the sheet metal covering. 45

In testimony whereof I affix my signature.
NEWTON L. HALL.
